UNITED STATES PATENT OFFICE.

JACOB G. LEIBOLD, OF SAN FRANCISCO, CALIFORNIA.

DESIGN FOR A SHIRT-FRONT.

56,982.

Specification for Design.

Patented Jan. 25, 1921.

Application filed October 2, 1918. Serial No. 256,611. Term of patent 7 years.

To all whom it may concern:

Be it known that I, JACOB G. LEIBOLD, a citizen of the United States, and a resident of San Francisco, in the county of San Francisco and State of California, have invented a new, original, and ornamental Design for a Shirt-Front, of which the following is a specification, reference being had to the accompanying drawing, forming a part thereof.

In the drawing:

Fig. 2 is a back elevation of the shirt-front.

What I claim is:—

The new and ornamental design for a shirt-front substantially as shown.

In testimony whereof, I have hereunto set my hand this 25th day of September, A. D. 1918.

JACOB G. LEIBOLD.
